Primary Examiner — T Chase Nelson(74) Attorney, Agent, or Firm — Shook, Hardy & Bacon L.L.P.(57) CLAIM

The ornamental design for a shoe, as shown and described.

DESCRIPTION

FIG. 1 is a plan view of a shoe showing my design;
FIG. 2 is a first side perspective view thereof;

FIG. 3 is a second side perspective view thereof; and,
FIG. 4 is a front perspective view thereof.

The even-length broken lines are directed to environment, represent unclaimed subject matter, and form no part of the claimed design. The long and short broken lines form an unclaimed boundary around at least a portion of the claimed subject matter and form no part of the claim.
